UNITED STATES PATENT OFFICE.

JOSEPH T. ROFFY, OF PITTSBURGH, PENNSYLVANIA, ASSIGNOR TO THE STANDARD CORPORATION, A CORPORATION OF WEST VIRGINIA.

LIGHT PROJECTOR.

Application filed November 17, 1920. Serial No. 424,641.

To all whom it may concern:

Be it known that I, JOSEPH T. ROFFY, a citizen of the Republic of Hungary, and a resident of Pittsburgh, in the county of Allegheny and State of Pennsylvania, have made a new and useful Improvement in Light Projectors, of which the following is a specification.

This invention relates to illuminating apparatus and more especially to headlights and spot lights for use on vehicles.

An object of this invention is to provide a light projector comprising a glass mold-blown optical unit and a housing or casing for properly supporting the same.

A still further object of this invention is to provide a light projecting device having a minimum number of parts and having such parts of cheap construction and easy assembly.

To clearly illustrate the invention, I have shown an embodiment thereof in the drawing accompanying and forming part of this application and in which the single figure 25 represents a sectional elevation of a light projecting device embodying this invention.

The optical unit 1 consists of reflector portions 2 and 3 an annular connecting portion 4 and an aperture closing or front glass 5. 30 This is mold-blown as an integral structure and the reflecting portions 2 and 3 are preferably externally silvered, as shown by the heavy lines 2^a and 3^a. For the convenience of manufacture, the connecting portion 4 is 35 also externally silvered as shown at 4^a.

It will be understood that the reflector portions, if desired, may be internally silvered, and while this method may increase the initial efficiency of the device, it is preferable, to use the external silvering as this 40 may be protected by a protective cover of suitable paint, as is now common in mirror manufacture.

The term "silvering" is used in its broad 45 sense and contemplates any mirror surface formed by any of the metals now used, such as gold, silver, nickel, etc.

In order to protect and properly house the optical unit which of necessity is somewhat 50 fragile and to form a support for the electric incandescent lamp used as the light source, a metal housing or case, preferably formed of two steel stampings 8 and 9 is used. These stampings, as will be understood, 55 may be of any contour desired but

the back of stamping 8 will preferably be so formed as to engage the peripheral edge 10 of the optical unit. The front stamping 9 preferably overlaps the forward edge of stamping 8, as shown at 11 and its forward edge 12 which will have more or less spring, 60 yieldingly holds the unit in position within the housing in such a manner that the silvered surfaces are out of contact with the housing.

Stamping 8 is provided with a flanged opening, (the flange being numbered 13) and a block 14 snugly fits within said flange, and is held in place by means of a set screw 15.

Block 14 is provided with a central bore 16 adapted to receive a lamp socket 17 of standard construction. An electric incandescent lamp 18 of suitable type and candle power, is employed as the source of illumination and socket 17, carrying the lamp may be moved axially to allow the filament 19 of the lamp to be placed in proper focal relation to the optical system. The set screw 15 serves as a lock for socket 17.

While I have shown a standard form of switch 20, it will be understood that any type of switch may be used.

The tip 21 of the lamp bulb with this optical system is preferably frosted, as is the case with the lamp bulb of my Patent No. 1,245,512.

I claim:

In a light projector, a blown glass unit comprising a reflector portion and a forwardly bulging portion serving as a cover and joining said reflector portion at the point of the unit's greatest circumference, a shell or casing comprising a rear portion spaced from the reflector portion of the glass unit except at its greatest circumference where the shell or casing is provided with a seat against which the glass unit rests and an annular casing closing member overlapping the front portion of the shell or casing and extending forwardly of the casing unit and out of contact therewith to a point where the circumference of the glass unit is materially less than its greatest circumference.

In testimony whereof, I have hereunto subscribed my name this 15th day of November, 1920.

JOSEPH T. ROFFY.
